UNITED STATES PATENT OFFICE.

HENRY D. DEAM, OF BENTON HARBOR, MICHIGAN.

SHIP-FLOATING MEANS.

1,319,378.

Specification of Letters Patent. Patented Oct. 21, 1919.

Application filed March 18, 1918. Serial No. 223,136.

To all whom it may concern:

Be it known that I, HENRY D. DEAM, a citizen of the United States, residing at Benton Harbor, in the county of Berrien and State of Michigan, have invented certain new and useful Improvements in Ship-Floating Means, of which the following is a specification.

This invention relates to ships and vessels of all kinds, and has for its object the production of apparatus adapted to keep the ship to which it is attached afloat when the ship has been injured, or, for any reason, is in danger of sinking. A special object 10 of the invention is to provide apparatus which, while normally not in position for service, yet may be quickly placed in position; and also for providing operating means for placing the apparatus in 15 position when desired. Other objects of the invention will be apparent upon a consideration of the drawings and the description thereof.

Of the accompanying drawings Figure 1 20 is a vertical sectional view of a portion of the side of a vessel, with apparatus attached thereto, which embodies features of my invention. Fig. 2 is a similar view with part 25 of the apparatus in place and in condition to prevent sinking of the vessel. Fig. 3 is a similar view with other elements in use. Figs. 4 and 5 are enlarged detail views of 30 a portion of the apparatus shown in Figs. 1 and 2; and Figs. 6 and 7 are enlarged detail views of the means for operating the 35 ship floating mechanism. And Fig. 8 is an elevation of a complete unit in use.

The general method which I have invented to prevent sinking of the vessel is an improvement on the invention illustrated and 40 described in an application for a patent, Serial No. 117,253, filed by William Schneider, Aug. 28, 1916, in which bags are provided which may be fastened to the side 45 of the vessel and may be filled with air, or other suitable gases, so that the buoyancy of the bags, taken in connection with such buoyancy of the vessel itself, as may exist, would be sufficient to float the vessel. The 50 apparatus which I use comprises a large number of bags 10, which are suitably attached to the sides of the vessel, and which, normally, are supported near the upper portion of the sides of the vessel in any suitable manner, as is indicated in Fig. 1. These bags may be of any suitable size; I

prefer the bags to be of sufficient length to reach when distended a very material distance down the side of the vessel, and to have when fully inflated a horizontal cross-section of perhaps from 15 to 25 feet, it being understood, however, that these dimensions are not material to the merits of my invention. The bags also may be made of any suitable material. I prefer for the purpose flexible material which not only is airtight and water proof, but which would not be injured by the ordinary salt water of the seas. The upper portion of these bags is fixed in any suitable manner to the upper portion of the 60 sides of the vessel. In this instance I have shown them fastened by bolts 11, and also by pipes 12 which, at the same time, provide means for passing air or any suitable 65 gas into the bags when they are to be distended. Any suitable means for supplying compressed gas may be provided. I prefer for the purpose compressed air tanks 22 connected to the bags by means of pipes 12.

Fixed to that portion of the bag, which is 70 the lower portion when the bags are in use, is a hook 13, and fixed to each end of these hooks is a cable 14, which, normally, as indicated in Fig. 1, passes downwardly 75 through the opening 15 in the side of the vessel, and around the pulley 16, which is inclosed in the water tight compartment 17. The cable then passes upwardly through the pipe 18 screwed into the casing 19 of the compartment. Passing out of the upper 80 end of the pipe 18 the cable is wound around a windlass 20, and from thence passes over a pulley 21, and downwardly, connecting 85 with the upper end of the hook 13; and it is also connected to the bag by the connector 25.

Any suitable means may be provided for 90 operating the windlass 20. The means which I prefer are hereinafter described. The cable is prevented from slipping on the 95 windlass in any suitable manner; and an inspection of Fig. 1 will show, that, when the windlass is rotated in the proper direction, the hook 13, and hence, the portion of the bag to which it is attached will be 100 pulled downwardly and the hook will finally be drawn by the cable into the compartment 105 110 sufficiently so that when the windlass is rotated slightly in the opposite direction the hook will become attached to the side of the vessel at the point 23, and this will firmly hold the hook in place, and, hence, the lower

end of the bag, as indicated in Fig. 2. When in this position, if compressed gas is forced into the bag the bag will become inflated, as indicated in Fig. 2; and if a sufficient number of bags are thus inflated along the sides of the vessel, the vessel will be floated, even though, due to the inflow of water, the buoyancy of the vessel is largely destroyed.

- 10 When it is desired to replace the bags to normal position, the gas may be exhausted therefrom in any suitable manner, and the hooks 13 may be released by any suitable means, such as by means of poles with suitable tools on the ends, and the windlasses 20 rotated to lift the bags. By suitably connecting the bags to the cable 14 at the point 25, as the bags are pulled upwardly they will fold automatically and ultimately 20 will assume the position indicated by Fig. 1, being entirely removed from the water and suspended from the upper portion of the sides of the vessel so as to be quickly available for future use.
- 25 The means which I prefer for operating the various windlasses comprises a lever 30 which has a forked end adapted to pass over the projecting axis 31 of the windlass. By lifting upwardly on the free end of the lever, 30 the windlass will be rotated to pull the bag downwardly, and the pawl 32 will prevent backward rotation of the windlass. By using the lever on the other side of the windlass, and forcing the free end downward, after releasing the hook 13 and the pawl 32, the windlass will be operated to raise the bags, the pawl 33 preventing backward rotation.

When, for any reason, it is feared the vessel may sink all of the bags on both sides of the vessel, or so many of them as may seem advisable, are pulled down to their operating position, either simultaneously, or successively, as may be desired; and compressed air is then passed into the bags in any suitable manner sufficiently to keep the ship afloat. Inasmuch as each bag and its operating mechanism is a unit by itself and is independent of each of the other bags and 45 mechanism injury to any one or more of the units will not affect the other units; so that such injury unless very comprehensive, would not prevent floating of the ship.

In order to protect the bags when in normal position and not in use, any suitable means may be provided. I prefer for the purpose metallic sheets 26, rotatably suspended at some suitable point at the side of the vessel by means of suitable apparatus 27, 55 and extending downwardly below the edge of the bags, being held in place at the lower ends when thus supported by means of the rods 28 passing through openings 29 in the sides of the vessel. When the bags are lowered and inflated for use these protection

plates 26 are forced upwardly, as indicated in Fig. 2, by the upward pressure of the bags against the lower sides of the plates 26, and are supported by the rods 28. The plates serve the double purpose of assisting in supporting the vessel and of protecting the bags from rupture at the point where the maximum pressure occurs. When the bags are allowed to collapse and are elevated the rods 28 pass into the vessel through the openings 29 and drop downwardly, as indicated in Fig. 1, holding the sheets 26 in place.

Bolts 11 pass through the bags, and thus hold the upper ends of the bags firmly in place. And wings 36 may be fixed to the hooks 13 to prevent their turning sidewise.

The inflated bags frequently will cover small openings which may be produced in the side of the vessel, and prevent the inrush of water therein. I have provided additional means for preventing the inrush of water through openings, of any nature, made, in any manner, through the sides of the vessel; so as to maintain as great as possible the buoyancy of the vessel itself. These means comprise mattresses 40 which are to be used connected, in any suitable manner, for example by means of cords 41, and hooks 42, to eyes 43, fixed to the hooks 13; the upper edges of the mattresses being supported by means of cords 44 and hooks 45, hooked to the upper side of the vessel. Whenever it is desired to cover an opening in the side of the vessel the bags 10 opposite the opening are lowered in the usual manner, and sheets 100 or mattresses 40, fixed to the hooks 13 which are associated with such bags, are lowered, with the mattresses placed in such a manner as to cover the opening. The pressure of the water then forces the bags and the mattresses against the side of the vessel and will prevent any very material inflow of water through the opening. The mattresses may be of any suitable size and any suitable material and reinforced in any suitable manner. In order to more completely fill the hole compressed air may be passed into the bags under the mattresses. Compressed air for the purpose, and for filling the bags completely at any time may be obtained from the compressed air tanks 22.

From this it will be seen that by inflating a suitable number of bags the vessel may be floated even though a large amount of water may flow through openings into the interior; but by the use of the mattresses in a proper manner, thus reducing or eliminating the inflow of water, the number of inflated bags may be materially reduced; or the vessel under the most serious circumstances may be floated temporarily or permanently.

I claim as my invention:

1. In a ship, a chamber in the lower portion of said ship, an opening through the side of said ship into said chamber, a guide

- mounted in said chamber, an opening in the upper portion of said chamber, a guide mounted in said ship, a cable passing through said first mentioned opening into said chamber, around said guide and upwardly through said second mentioned opening and around said second mentioned guide, means for moving said cable longitudinally, and a bag fixed to said cable.
- 5 2. In a ship, a chamber in the lower portion of said ship, an opening through the side of said ship into said chamber, a guide mounted in said chamber, an opening in the upper portion of said chamber, a guide mounted in said ship, a cable passing through said first mentioned opening into said chamber, means for moving said cable longitudinally, a bag fixed to said cable, and a hook fixed to said cable adapted to hook 10 into the edge of the opening in the side of said ship when said cable is moved so as to carry said bag downwardly.
- 15 3. A ship in combination with a bag, the upper edge of said bag being permanently fastened to the upper portion of one side of said ship, means fixed to the lower edge of said bag for pulling said latter edge downward, means for filling said bag with gas, and means independent of said pulling down 20 means for locking said bag in its downward position, said means comprising an opening in the side of said vessel and a hook adapted to hook into said opening.
- 25 4. A ship, a pulley supported by the upper portion of one side of said ship, a pulley supported by the lower portion of the side of the ship, a cable passing around both of said pulleys, one branch of said cable being positioned inside of the ship, a bag 30 fixed to said cable, and means for moving said cable around said pulleys in either direction, whereby a portion of said bag may be pulled downwardly or upwardly along the side of said ship.
- 35 45 5. A ship, a pulley supported by the upper portion of one side of said ship, a pulley supported by the lower portion of the side of the ship, a cable passing around both of said pulleys, one branch of said cable being positioned inside of the ship, a bag fixed to said cable, and means for moving said cable around said pulleys in either direction, whereby a portion of said bag may be pulled 40 downwardly or upwardly along the side of said ship, and means for locking said cable from backward movement when said bag portion has been moved downwardly.
- 45 6. In a ship, a chamber in the lower portion of said ship, an opening through the side of said ship into said chamber, a guide
- 5 65 mounted in said chamber, an opening in the upper portion of said chamber, a guide mounted in said ship, a cable passing through said first mentioned opening into said chamber, around said guide and upwardly through said second mentioned opening around said second mentioned guide, and over the side of said ship, the ends of said cable being connected, means for moving said cable longitudinally, and a bag fixed to said cable.
- 10 7. In a ship, a chamber in the lower portion of said ship, an opening through the side of said ship into said chamber, a guide mounted in said chamber, an opening in the upper portion of said chamber, a guide mounted in said ship, a cable passing through said first mentioned opening into said chamber, around said guide and upwardly through said second mentioned opening around said second mentioned guide, and over the side of said vessel, the ends of said cable being connected, means for moving said cable longitudinally, a bag fixed to said cable, and a hook fixed to said cable adapted to hook into the edge of the opening in the side of said ship when said cable is moved so as to carry said bag downwardly.
- 15 8. A ship in combination with a bag, the upper edge of said bag being permanently fastened to the upper portion of one side of said ship, means fixed to the lower edge of said bag for pulling said latter edge downward, means for filling said bag with gas, and means independent of said pulling down means for locking said bag in its downward position.
- 20 9. A ship in combination with a bag, the upper edge of said bag being permanently fastened to the upper portion of one side of said ship, means fixed to the lower edge of said bag for pulling said latter edge downward, and a flexible sheet with its lower edge connected to the latter means adjacent the lower edge of said bag.
- 25 10. A ship in combination with a bag, the upper edge of said bag being permanently fastened to the upper portion of one side of said ship, means fixed to the lower edge of said bag for pulling said latter edge downward, and a flexible sheet with its lower edge connected to the latter means adjacent the lower edge of said bag, and means for connecting the upper edge of said sheet to the upper portion of the side of said vessel.
- 30 110 115 In testimony whereof, I hereunto set my hand.

HENRY D. DEAM.
